(57) **CLAIM**

The ornamental design for a cable, as shown and described.

DESCRIPTION

FIG. 1 is a front view of a cable comprising a new, original and ornamental design;

FIG. 2 is a right-hand side view, with the left-hand side view being a mirror image thereof;

FIG. 3 is a rear view thereof;

FIG. 4 is a top view thereof; and,

FIG. 5 is a bottom view thereof.

The broken line portion of the figure drawings is included to show unclaimed subject matter only and forms no part of the claimed design.
